UNITED STATES PATENT OFFICE.

ALEXANDER M. GOW, OF DULUTH, MINNESOTA.

DOOR FOR SIDE-DUMP CARS.

1,210,462.

Specification of Letters Patent. Patented Jan. 3, 1917.

Application filed February 17, 1916. Serial No. 78,909.

To all whom it may concern:

Be it known that I, ALEXANDER M. Gow, a citizen of the United States, and resident of Duluth, in the county of St. Louis and State 5 of Minnesota, have invented certain new and useful Improvements in Doors for Side-Dump Cars, of which the following is a specification.

My invention relates to dumping cars and 10 has particular reference to a novel door for use in connection with cars of the bodily tilting type.

It is evident that with a large car of the side dumping type, wherein the door is necessarily suspended from its two ends, the 15 bending strain is very great, due to the pressure of the load. To overcome this bending strain, it has been customary to reinforce the door with tie rods, and these having proved 20 inefficient and insufficient, the customary practice is to make the doors of square, box-girder section, consisting of vertical inner and outer plates separated at the top and bottom with channel irons or Z-bars. Such 25 construction, while an advance over the tie rod construction, is weak in that it does not present the greatest resistance at the point of greatest strain, namely at the top edge of the door. When a car of this type is loaded with 30 heavy material as, for instance, ore or rock and boulders, it is evident that there is practically no strain on the bottom edge of the door, while the top edge is under maximum strain or outward pressure. In addition, the 35 top, or upper edge, is subject to the severe impact of the material when the car is being loaded. It is clear then that a door designed to resist the strain to which it is subjected, should have a maximum of strength at its 40 top edge and a minimum of strength at its bottom edge. Furthermore, when the car begins to tilt, or dump, the door should be so designed as to free itself from the pressure of the load that it may rise with a minimum 45 of resistance. To accomplish this end many devices have been employed to cause the bottom of the door to swing outwardly, coincident with its upward movement, such devices involving a complication of levers and 50 moving arms which have been the basis of several patents.

My construction involves making a door which shall have a maximum strength at its top edge and a minimum strength at its bottom edge, and by its taper form shall relieve itself from the pressure of the load as the

car is dumped. To accomplish these ends, I propose to make a door whose outside shall be practically vertical, but whose inside shall be inclined, or sloping. By so doing I no- 60 wise decrease the capacity of the car, for what I lose in increased width at the top I gain by decreased width at the bottom. I thus am enabled to build a door having strength sufficient to resist the strains and 65 blows at the point where they come, namely, at the top edge of the door, without decreasing the capacity of the car. In addition, I am enabled to build a door of less weight and 70 cheaper to fabricate.

The invention will be more readily understood by reference to the accompanying drawings, wherein—

Figure 1 is an end elevation of a car to which my improvement is applied; Fig. 2 is 75 a transverse section through the door shown in the car of Fig. 1; Fig. 3 is a section on the line 3—3 of Fig. 2; Fig. 4 is a section through a door of modified form; Fig. 5 is a section on the line 5—5 of Fig. 4; Fig. 6 80 is an edge elevation of the gusset employed in the construction of Figs. 4 and 5, Fig. 7 is a sectional view through a still further modification, and Fig. 8 is a section on the line 8—8 of Fig. 7.

Referring more particularly to the drawings, it will be seen that a car body 10 of the type contemplated by me is mounted for oscillation on suitable brackets 11 mounted on the bolsters 12. The doors 13, which act 90 as the closures for the sides of the box or car body are mounted on arms 14, pivoted at 15. Connected to the arms 14 intermediate their ends are links 16, to the lower ends of which links are connected links 17, pivoted to the 95 brackets 11. The lower ends of the links 16 normally rest upon the bolsters 12 or a similar supporting element. The arrangement is such that as the car body tilts the body and the door assume the dotted-line positions of 100 Fig. 1.

My invention relates to the construction of a door, the form of which may be varied somewhat, as indicated in Figs. 2 to 8. In Figs. 2 and 3 it will be seen that I provide 105 a door composed of an outer vertical plate 18, an inner inclined plate 19, a top channel 20, a bottom bar 21 and a gusset 22 joined to the inner and outer plates by means of angles 23. In Figs. 4 and 5 the outer and inner plates 24, 25, respectively, and the bottom filler 26 remain the same as shown in 110

Fig. 2. The top member 27, is, however, semi-circular in cross section, and the gusset 28 is joined, not only to the inner and outer plates, but to the top member as well. The 5 specific form of the gusset is shown in elevation in Fig. 6. In the construction of Figs. 7 and 8 both the inner and outer plates 29, 30, are inclined, the same being directly joined at their lower edges. The top member 10 consists of a semicircular plate 31, similar to that shown in Fig. 4, while the gusset 32 may be of a common form. In the construction of Figs. 2 to 6 inclusive it will be seen that the outer wall of the door is vertical while the inner wall is inclined. The 15 exact shape of the outer wall is immaterial, except in that it should be so designed as to provide proper strength. However, the downward and outward inclination of the 20 inner wall provides the function of lessened resistance in clearing the load in the car. It likewise provides for an increased thickness at the top of the door where the greatest strength is needed.

25 It will be understood that the invention contemplates the employment of a wide, longitudinally extending upper member and a relatively narrow longitudinally extending lower member and a plate connecting said 30 members, together with means either in the form of a plate, braces, posts, etc., for connecting the free edges of the top and bottom members. While the preferred construction 35 contemplates the employment of inner and outer plates in order to secure the requisite strength, it will be understood that an advantageous result may be secured from certain modifications of that construction.

Obviously the construction is capable of 40 other modifications than those herein shown, and such modifications as are within the scope of my claims I consider within the spirit of my invention.

I claim:

45 1. In a car body adapted to be dumped sidewise, a door having maximum transverse strength at its top edge, and minimum transverse strength at its bottom edge, and of substantially triangular cross section, the 50 base of the triangle being uppermost.

55 2. In a door of the class described, the combination of inner and outer plates, said inner plate being inclined with relation to the vertical, thereby forming a structure which is of greater transverse thickness at the top of the door than at the bottom, and interior stiffening means between said inner and outer plates, substantially as described.

60 3. A skeleton door, substantially triangular in cross section and composed of inner

and outer plates, said inner plates being inclined with relation to the vertical, and top and bottom members spacing said plates apart, said upper member having a transverse strength materially greater than said 65 bottom member.

4. A dump car door, comprising a longitudinal top member, a longitudinal bottom member of less transverse strength than the top member, a longitudinal plate secured at 70 its top and bottom edges to the members, and stiffening members secured to the plate between the top and bottom members, the whole forming a structure of substantially triangular shape, having the base uppermost. 75

5. A dump car door, comprising longitudinally extending top and bottom members, an uprightly disposed longitudinal plate secured to the members at its top and 80 bottom edges, the transverse depth of the bottom member being less than the transverse depth of the top member, the whole forming a structure of substantially triangular shape, having the base uppermost. 85

6. In a car body adapted to be dumped sidewise, a door having a wide longitudinally extending top member and a relatively narrow longitudinally extending bottom member, a plate connecting said members 90 and stiffening members of substantially triangular shape disposed vertically between the top and bottom members and secured to the plate.

7. A dump car door, comprising a structural steel beam having a progressively variable transverse strength and depth, this transverse strength and depth being maximum at the top edge and minimum at the bottom edge, the beam being of substantially 100 triangular cross section, having the base uppermost.

8. In a car body adapted to be dumped sidewise, the combination of a door having a wide, longitudinally extending top member and a relatively narrow, longitudinally extending bottom member, a plate connecting the inside edges of said top and bottom members, and stiffening means for said plate, the door having a progressively variable 105 transverse strength, this strength being maximum at the top edge and minimum at the bottom edge, substantially as described. 110

Signed at Duluth, Minn., this 14" day of February, 1916.
